CLAIM

The ornamental design for a vehicle seat, as shown and described.

DESCRIPTION

FIG. 1 is a perspective view of a vehicle seat incorporating my new design, viewed from in front of, above, and from the left side thereof;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in FIGS. 1-7 form no part of the claimed design and include dot-dashed lines that define the bounds of the claimed design and dashed lines that illustrate portions of the vehicle seat that form no part of the claimed design.
